DRIP RECEPTACLE FOR UMBRELLAS

Filed Dec. 18, 1941

OSCAR AMBROSE BARDY
INVENTOR.

BY

Alexander Gleicher
ATTORNEY

For purposes of operation, it can be seen that when the main umbrella is closed, the loose connections or threads 22' between loops 22 and 26 cause ribs 23 of the drip receptacle device to collapse about securing ring 14. Any water that flows from the umbrella covering 19 will be trapped on the inside of the auxiliary covering 25 while the water on the outside surface of covering 25 will be trapped within the cup 29. When the umbrella is opened, covering 25 becomes stretched over ribs 23, the lower ends of said ribs resting on the stretched umbrella covering 19. If there has been any trapped water inside covering 25 and cup 29, such water will flow down the main umbrella covering 19 when opened and thereby fall free of and around the user of the umbrella.

It is to be noted that screw 30 is provided with a flat head 30' so that in the use of the umbrella as a walking stick, the flat portion 28 of drip cup 29 will not wear out by contact with the ground. It is also to be noted that the distance between securing rings 13 and 14 may be varied to bring the auxiliary covering 25 in closer proximity with covering 19 and that the connecting threads 22' between loops 22 and 26 may vary in length to bring the covering 25 when collapsed closer to the covering 19.

I wish it understood that minor changes and variations in the integration, construction, location and material of the parts of the invention as shown may be resorted to without departing from the spirit of the invention and the scope of the appended claims.

I claim:

1. In an umbrella, a drip attachment comprising an outer auxiliary covering disposed above the main umbrella covering, a plurality of ribs supporting said auxiliary covering and being pivotally secured to the umbrella stick, and a

cup member securable to the end of the umbrella stick and serving to clamp a part of the auxiliary covering therebetween and being adapted to receive water from the outer surface of the auxiliary covering when in a closed position.

2. In combination with an umbrella, a collapsible auxiliary covering secured to an end portion of the umbrella stick, a cup member securable to the umbrella stick end and serving to clamp a part of the auxiliary covering therebetween and being adjacent to said auxiliary covering and adapted to receive water from the outer surface of said auxiliary covering when in collapsed position.

3. In combination with an umbrella, a collapsible auxiliary covering secured to an end portion of the umbrella stick, means to secure said auxiliary covering to the umbrella covering whereby the closing of the main umbrella covering causes the closing of the auxiliary covering, a cup member securable to the end of the umbrella stick adjacent said auxiliary covering and adapted to receive water from the outer surface of said auxiliary covering when in collapsed position.

4. In combination with an umbrella, a collapsible auxiliary covering secured to an end portion of the umbrella stick, the outer edges of said auxiliary covering being adjacent the main umbrella covering whereby the auxiliary covering is forced open upon the opening of the main umbrella covering, means to secure said auxiliary covering to the umbrella covering whereby the auxiliary covering closes with the closing of the umbrella covering, and a cup member securable to the end of the umbrella stick adjacent said auxiliary covering and adapted to receive water from the outer surface of said auxiliary covering when in collapsed position.

OSCAR AMBROSE BARDY.
